UNITED STATES PATENT OFFICE.

LEW ARNTZ, OF DES MOINES, IOWA.

SAFETY HOLDER FOR PENS AND PENCILS.

Application filed December 3, 1923. Serial No. 678,224.

To all whom it may concern:

Be it known that I, LEW ARNTZ, a citizen of the United States, and a resident of Des Moines, in the county of Polk and State of Iowa, have invented a certain new and useful Safety Holder for Pens and Pencils, of which the following is a specification.

The purpose of my invention is to provide a safety holder which can be used for holding a pen or pencil in the pocket in such manner that there is practically no likelihood of losing the pen or pencil.

More particularly, it is my object to provide such a holder having an engaging member, a projecting arm and an adjustable element adapted to project to position for engaging the cloth of a pocket to prevent the removal of the pencil or pen or to position where it is inoperative.

20 A further purpose is to provide such a device having novel features of construction whereby the desirable purposes above mentioned can be accomplished.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a sectional view of a pocket having a pencil therein with my invention installed thereon.

35 Figure 2 shows a front elevation of my holder.

Figure 3 shows a vertical, sectional view taken on the line 3—3 of Figure 2.

40 Figure 4 shows a rear elevation of my holder; and

Figure 5 shows a horizontal, sectional view taken on the line 5—5 of Figure 2.

It frequently occurs that valuable pencils or pens are lost from the pocket of the user owing to the lack of some satisfactory means for preventing the accidental dropping out of the pencil or pen. I have provided in my present invention a means for avoiding such loss.

50 My invention comprises an attaching means, which as illustrated in the accompanying drawings comprises a split ring or band indicated by the reference character 10 made of resilient material and commonly

employed. Projecting from the lower edge 55 of the band 10 is a resilient arm 11, which is inclined outwardly slightly and thence inwardly again and terminates in a ball or the like 12.

The structure so far described is not novel 60 and of itself does not constitute my invention.

It is found, however, that the structure heretofore described, which is illustrative of the devices commonly used, is not always 65 effective in preventing the loss of a valuable pen or pencil.

I have therefore provided in the arm 11 a slot 13 extending through the arm from front to rear as shown in Figure 3 for instance. The wall of the slot 13 at its inner upper part is tapered from the front upwardly and rearwardly as at 14 and communicates at its upper end with a groove 15 extending upwardly from the slot on the 70 inner face of the arm 11 for a short distance and growing more shallow toward its upper end.

Extended through the slot 13 is a catch element comprising a piece of flat spring 80 16, the upper end of which is on the inner side of the arm and the outer end of which projects downwardly on the outer side of the arm, as shown in Figure 3.

The outer lower end of the spring catch 85 element 16 has a shoulder or shoulders 17 shown for instance in Figures 1 and 2.

Extended through the lower end of the spring catch member 16 is a member or device which serves several purposes.

As shown, this device consists of a small screw bolt 18, the head of which is on the inner side of the arm 12. The shank extends through the slot 13 and through the lower end of the spring catch element 16.

On the outer end of the screw bolt 18 outside the spring catch element 16 is mounted a nut 19, which is adjustable on account of its screw-threaded connection with the screw bolt.

100 The parts are so connected that when they are assembled, the shoulder 17 bears against the outer face of the arm 12 and the upper portion of the spring catch element 16 bears against the bottom of the groove 15 with the 105 spring catch element bent to slightly curved position as shown for instance in Figure 3.

The inner face of the arm 12 is preferably

provided near the lower end of the slot 13 with counter sinkings 20 to receive the head of the screw bolt 18.

The parts are so arranged that the spring 5 catch element 16 may be slid upwardly or downwardly. When it is in its lower position, the head of the screw bolt 18 is received in the lower counter sinking 20 and the tension of the spring catch element 16 10 tends to pull the bolt outwardly for thus holding the head in the counter sinking and preventing any sliding movement of the spring catch element.

When the parts are in this position, the 15 upper end of the spring catch element 16 is received in the groove 15, so that it does not project inwardly at least to any substantial extent from the inner surface of the arm 12.

When it is desired to move the spring 20 catch element to operative position, the lower end of the spring catch element is pushed toward the arm 12 to enable the head of the screw bolt 18 to clear the lower counter sinking and then the spring catch 25 element 16 is shoved upwardly until its upper end projects inwardly from the inner face of the arm 12 and upwardly as shown by dotted lines in Figure 3 and in full lines in Figure 1.

When the manual pressure on the lower 30 end of the spring catch element 16 is released, the tension of that element will swing its lower end outwardly again, so that the head of the screw bolt 18 will enter the 35 upper counter sinking 20, as shown by dotted lines in Figure 3.

It will be seen that when the catch element is in its last mentioned position, and the device is mounted on a pen or pencil, the 40 pen or pencil can be shoved into the pocket 21 with the arm 11 on the outside, and that the upper end of the catch device will engage the cloth of the pocket, as at 22, and prevent any accidental removal of the pencil 45 or pen from the pocket.

When, however, the user desires to remove the pencil, he can push the lower end of the member 16 toward the arm 11 for allowing the head of the screw bolt to clear the 50 counter sinking 20 and shove the catch ele-

ment downwardly until it will be released from engagement with the cloth of the pocket.

It will be seen from the foregoing that my device will hold a pencil or the like in a 55 pocket with a minimum danger of loss.

It will be seen from the drawing that the upper wall of the slot 13 and the bottom of the groove 15 are so inclined as to deflect the upper end of the member 16 inwardly 60 when said member 16 is moved to its upper position as illustrated in dotted lines in Figure 3, while, when the member 16 is moved to its lower position, it does not project from the inner side of the arm 12 and 65 will, therefor, when in the latter position, not injure the cloth of the pocket during the removal of the pen or pencil from the pocket.

My invention may be modified as to the 70 construction and arrangement of its parts without departing from its real spirit and purpose, and it is my intention to cover by my claims, any modified forms of structure or use of mechanical equivalents, which may 75 be reasonably included within their scope.

I claim as my invention:

1. In a holder of the class described, means for engaging a pen, pencil or the like, an arm thereon, a resilient catch element 80 slidably mounted in said arm for adjustment from position with an end substantially flush with the arm to position with the end projecting from the arm and vice versa, and means for holding said element in different 85 positions of its adjustment.

2. In a holder of the class described, means for engaging a pen, pencil or the like, an arm thereon having a slot therein and a groove in one side communicating with said 90 slot, a resilient catch element projected through said slot and capable of sliding movement from position with one end in said groove to position with said end projecting from the arm, and means carried by 95 said element for coacting with the arm for holding the element in different adjusted positions.

Des Moines, Iowa, November 23, 1923.
LEW ARNTZ.
